UNITED STATES PATENT OFFICE.

DAVID F. HARTFORD, OF BOSTON, MASSACHUSETTS, ASSIGNOR TO UNITED SHOE MACHINERY COMPANY, OF PATERSON, NEW JERSEY, A CORPORATION OF NEW JERSEY.

ROUNDING-MACHINE TOOL FOR SOLE-CUTTING.

SPECIFICATION forming part of Letters Patent No. 767,754, dated August 16, 1904.

Application filed September 1, 1899. Renewed May 18, 1901. Serial No. 60,936. (No model.)

To all whom it may concern:

Be it known that I, DAVID F. HARTFORD, of Boston, in the county of Suffolk and State of Massachusetts, have invented a new and useful Improvement in Rounding-Machine Tools for Sole-Cutting, of which the following is a specification.

In cutting soles by means of a pattern a rounding-machine has been used having an oscillating block on which are mounted a gage and knife. As it is often desirable to be able to cut the soles a little larger than the pattern, either to compensate for the wear on the edge of the pattern or to give the sole an extra width, the position of the knife or knife-holder on the block has been adjusted. This method of adjustment, however, is not always satisfactory, for the reason that in these machines the block oscillates on its supporting-arm, and it is best that the knife-edge should always have a fixed relation to the axis of oscillation, preferably a little in advance of it. Any adjustment of the knife changes this relation, and hence to that extent renders the machine less satisfactory.

My improvement is intended to overcome the difficulties referred to; and it consists in a tool for use in a rounding-machine having an adjustable gage, by means of which the relation of the knife-blade and the axis of oscillation to the edge pattern may be adjusted according to the relation which it is desired to maintain between the size of the sole to be cut and the pattern. This construction is especially useful, because where the main adjustment is secured by changing the position of the gage the knife-edge may be maintained in a substantially fixed position with relation to the axis of oscillation, and thus accomplish more economical cutting results than if the movement of the knife were relied on solely to compensate for the wear on the edge of the pattern or give the sole an extra width. I have shown my invention in the drawings in its preferred form both applied to a wheel-gage, such as is used in connection with a sheet-metal pattern, and also to a non-rotating gage, such as is used when the pattern is of

wood or has a substantial thickness. The tool itself may be a combination-tool—that is, one in which the wheel-gage and the flat gage are interchangeable—or it may be constructed with a flat gage merely, and I have shown both forms in the drawings.

Figure 1 is a plan of a combination-tool having a wheel-gage and knife, Fig. 2 being a vertical section on the line 2 2 of Fig. 1. Fig. 3 is a plan of the block. Fig. 4 is a plan of the same tool, the flat gage and the knife-holder having been substituted for the wheel-gage, Fig. 5 being a vertical section on the line 5 5 of Fig. 4 and Fig. 6 a detail in perspective showing the knife-holder and gage separated. Fig. 7 is a plan of the form of tool having a permanent flat gage. Fig. 8 is a vertical section on the line 8 8 of Fig. 7, and Fig. 9 is a plan with the knife and knife-holder removed. Fig. 10 is a front elevation of this gage, showing especially the block common to all forms of the tool.

A is the arm of the rounding-machine, which, being well known to those skilled in the art, is not shown in full and need not be further described, and B is the ordinary sole-pattern, which may be thin, as indicated in Fig. 2, or may be thick, as indicated in Figs. 5 and 8.

The block, as is well known, consists of a portion C, which is attached to the arm A of the rounding-machine by rivets *a* and which has two trunnions, one, *c*, projecting from its upper side and the other, *c'*, projecting from its under side. The trunnion *c* sets into a bearing in a yoke-piece *c*², and the trunnion *c'* sets into a bearing in the plate D, the plate D and the yoke-piece *c*² being suitably connected—for example, by means of posts *c*³ *c*⁴.

In the combination-tool—by which I mean that form of rounding-machine in which the block carries a wheel-gage which is interchangeable with a flat gage—the preferred form of adjustment for the gage is as follows: The plate D has an opening *d* in its central portion, in which slides on suitable ways *d'* a slide-piece E, carrying the stud F, forming an axis for the wheel-gage G. The slide-piece

E has preferably in front of it a spring e , and an adjusting-screw e' bears against its rear, so that by turning this adjusting-screw in one direction the slide-piece E, carrying the gage-wheel G, is moved forward, and upon withdrawing the screw e' the slide-piece is pushed back by the spring e , this being merely a convenient way of adjusting the position of the slide-piece, and hence the gage. From the plate D project upward two bosses h h , and to the top of these bosses is attached, by means of screws, the knife-holder H, which is preferably yoke-shaped, as shown in Fig. 1, and serves not only as a knife-holder, but also to keep the wheel-gage G in place. It has a slot h^2 , and its upper surface is grooved. In this groove lies the washer h' , through which the set-screw h^3 passes downward into the stud F to guide the slide-piece when it is being adjusted and to set it in place after the adjustment has been made.

The front of the knife-holder is provided with a suitable opening j and set-screw j' , with which to set the knife J in place. This construction is such that when the set-screw h^3 is loosened the position of the wheel-gage may be adjusted either toward or from the pattern by turning the screw e' , and this will not affect the position of the knife, which will always be located with respect to the trunnions or axis of the block in the place where it is first put. When adjusted, the set-screw h^3 is tightened again.

The relation of the pattern to the gage is shown in Fig. 2, and it is usual to build up the pattern by means of a form, on which is placed and clamped the leather, so that the leather will be at a proper level to be acted upon by the knife J.

In Figs. 4, 5, and 6 I have shown the same block and plate D carrying a flat gage in place of the wheel-gage, intended to be used with a thick pattern where there is no necessity for the use of the form above referred to, the leather resting directly on the pattern. In this case the gage G' is shaped as shown in perspective in Fig. 6. It is provided with an opening which sets over the stud F upon the slide-piece E, and it is provided with a slot g , into which sets a pin g' on the under side of the knife-holder H' to prevent it from turning. The knife-holder H' differs from the knife-holder H mainly because it is cut under, as shown in Fig. 6 at g^2 , and the gage G' is thickened at g^3 to fit into this cutting under of the knife-holder, so that these parts may be brought together by adjustment and the front of the gage be made to lie in substantially the same plane with the front side of the knife K without unduly weakening the parts. To aid in this result, the knife shown has a shank which is flat on the inside and beveled on its front side, as shown in Fig. 5, to conform to the inner surface of the gage. The same result may be attained by bending

the shank of the knife to a proper angle and providing the knife-holder with a socket of proper shape to receive and hold it. I prefer, however, to use a knife which has a shank flat on the inside, as above described, and beveled on its front side, for in that case the position of the knife in the holder can be adjusted vertically without changing the relation of the edge of the blade to the axis of oscillation of the knife-holder. It will be noticed that in this case the knife-holder and flat gage are held in place by means of the same screws and parts that were used in holding the wheel-gage in place, as above described. The operation of this gage is the same as the operation of the wheel-gage. It is adjusted in and out by means of the screw e' , it being kept in alignment not only by means of the stud F upon the slide-piece E, but also by means of the slot g and pin g' , and it is set after adjustment by means of the washer h' and set-screw h^3 .

This combination-tool is of value in those shops where both thin and thick patterns are used, and hence it is desirable to change from one to the other; but in Figs. 7, 8, and 9 I have shown a simplified form of this flat gage, which will now be described. In this case the plate D is provided with means for preventing endwise movement of the set-screw e' . As shown, these means consist of an open-topped journal or fork f , which may be formed in the end of a stud set into an opening in the plate D. The set-screw is provided with two collars e^2 e^3 , located to bear one on each side of the journal f . The forward end of the set-screw passes into a threaded opening in the gage. The turning of the set-screw consequently moves the gage out or in. The knife-holder H holds the knife in the same way as is shown in Fig. 5, although, as the stud F is dispensed with, the knife-holder is shaped slightly differently. The tool is, in fact, a simplified form of the combination-tool, having the adjustable gage and the knife, which is non-adjustable. The gage being flat, the cut-under construction of the knife-holder and corresponding shape of the rear of the gage allow the knife-holder and gage to be brought in such relation that the plane of the gage will substantially coincide with the plane of the knife-edge, and this of course is, in fact, dependent not upon which of the two parts is adjustable with relation to the other, but upon the fact that the knife-holder and the knife-shank are so shaped that they will allow the knife-edge and gage to be brought together in the manner described without weakening the gage.

I do not mean to limit myself to the precise form of construction shown in the drawings, for it is evident that the adjustment of the gage with relation to the knife may be accomplished in other ways than that above described, as the essence of my invention consists in the relative adjustment of the gage

and knife irrespective of the means by which this adjustment is accomplished. The knife above described and shown in the drawings is also of my invention, but will form the 5 subject of a separate application.

What I claim as my invention is—

1. In a sole-rounding machine a pattern, a knife suitably mounted and a gage adapted to bear against said pattern, in combination 10 with means for adjusting the relative positions of the gage and the cutting edge of the knife.
2. In a sole-rounding machine a pattern, a knife suitably mounted and a gage adapted to bear against said pattern and having its 15 guiding edge adapted to be located in substantially the plane of the cutting edge of the knife, in combination with means for adjusting the relative positions of the guiding edge of the gage and the cutting edge of the knife.
3. In a sole-rounding machine, a knife suitably mounted and a gage having its guiding edge located in substantially the plane of the cutting edge of the knife and adjustable with 20 relation to said plane, as and for the purposes set forth.
4. In a rounding-machine an oscillating block carrying a knife and a gage, said gage having its guiding edge adjustable with relation to the cutting edge of the knife, as 25 described.
5. In a rounding-machine, a plate suitably mounted and carrying a knife stationary with relation to said plate, said plate also having a

stud adjustably located thereon and means whereby it may be adjusted, said stud carrying 35 a gage also sliding on said plate, all as set forth.

6. In a rounding-machine, a plate suitably mounted and having a sliding gage adjustably mounted thereon and a knife-holder mounted 40 on said gage having a knife located in its front, the front edge of said knife-holder being cut under and the upper portion of said gage being thinned as described, whereby it may be brought into substantially the same 45 vertical plane with the cutting edge of the knife.

7. In a rounding-machine, in combination with a knife provided with a shank beveled on its front side as described, an oscillating 50 block carrying a gage and a knife-holder, the one adjustable with relation to the other, said gage being thin at its upper edge and said knife-holder being shaped as shown, whereby when said knife-holder and said gage are 55 in contact, the cutting edge of said knife will be in substantially the same plane with the front of said gage, as and for the purposes set forth.

In testimony whereof I have hereunto set my 60 name this 28th day of August, 1899.

DAVID F. HARTFORD.
